UNITED STATES PATENT OFFICE.

WILLIS M. THOMPSON, OF MARQUETTE, MICHIGAN.

PADLOCK.

SPECIFICATION forming part of Letters Patent No. 631,389, dated August 22, 1899.

Application filed September 3, 1898. Serial No. 690,211. (No model.)

To all whom it may concern:

Be it known that I, WILLIS M. THOMPSON, a resident of Marquette, in the county of Marquette and State of Michigan, have invented 5 certain new and useful Improvements in Padlocks; and I do hereby declare the following to be a full, clear, and exact description of the invention, such as will enable others skilled in the art to which it appertains to make and 10 use the same.

My invention relates to improvements in locks, and more especially to that class known as "padlocks."

The primary object of my invention is to produce 15 a lock that will be impossible to "pick" and difficult to duplicate a key with which it may be operated.

A further object is to produce a lock having a number of tumblers that may be set in various 20 combinations and a key that may also be set to correspond with the combination of the lock in such manner that if an attempt to open the lock is made with other than its corresponding key it will become engaged and 25 impossible to remove to attempt further manipulation.

Illustrations of a lock embodying my invention are shown in the accompanying drawings, in which—

30 Figure 1 is a side view of a padlock embodying my invention. Fig. 2 is a longitudinal sectional view of the same. Fig. 3 is a cross-section. Fig. 4 is a detail of one of the tumblers. Fig. 5 is a plain view and section 35 through the key.

Referring to the drawings, wherein similar reference-letters indicate corresponding parts, I will now explain my invention.

A is a shell or casing provided at one end 40 with apertures for the reception of shackle B and at the opposite end is internally threaded to engage with threads on core C, which carries a knob c and a key-guide c', which terminates in a disk c², both the disk and shell 45 A being slotted to receive the shackle-arms b.

Passing through the key-guide c' is a rotating slotted guide D, which is flanged at its outer end, the flange being countersunk in the knob c and held in place by a pin d, passing through 50 the disk c² and engaging with a countersunk nut or washer d'. Arranged on shafts E on either side of the key-guide are the tumblers

F. Projections f on the tumblers F project normally into slots f' in the key-guide c' and are adapted to engage with the lugs h' of the 55 key. Opposite these projections f are the tumbler-locking arms f², which engage with notches b' in the shackle-arms b.

In order to hold the tumblers F in the notches b' of the shackle-arms b, I have provided 60 springs G, which are attached to the shafts E and press against the head of the pin g, fixed in the side of the locking-arms f².

In order to arrange combinations of the tumblers, it is necessary to hitch back one or 65 more of them, so that they will not operate. For this purpose the spring-hooks g² are fastened to the edge of the key-guide c', extending in such manner as to engage the pin-head g when the tumblers F are pressed down to 70 the side of the key-guide c', as shown in Figs. 3 and 4.

The key E consists of a shank slotted to receive dovetailed slide h, which retains the movable lugs h', as shown. These lugs are 75 provided with dovetailed and beveled heads that fit in suitable slots in the sides of the shank, and when placed in position the slide h is inserted and locks these in position. The object in having the lugs made movable is to 80 enable suitable combinations to be made to correspond with the combinations made with the tumblers in the lock proper. To change or set the combinations of the lock, as is evident, the case is removed. 85

To operate or lock and unlock, the combinations of the lock and those of the key are set to correspond or register and the rotating guide D set so that the slot in the knob c registers with the slot in the key-guide c', thus 90 allowing the key to be inserted its full length, when the lugs h' of the key will register with the slots f' in the key-guide c' and through them will engage the projections f on the tumblers F when the key is turned to the limit, 95 thereby throwing the locking-arms f² in and out of engagement with the notches b in the arms of the shackle, securing and releasing it as desired.

Having thus described my invention, what 100 I claim, and desire to secure by Letters Patent, is—

In a padlock the combination with a case and shackle, of spring-pressed tumblers F dis-

posed on shafts E parallel with the arms b of said shackle B adapted to be moved thereon and set to register with and engage the notches b' in said shackle-arms b, an outer key-guide 5 c' adjacent to said tumblers F having slots into which lugs on said tumblers may extend and engage the lugs of the key, a secondary key-guide extending through the said outer guide c' rotatably therein, spring-hooks attached to the sides of the said outer guide adapted to engage the pin-heads g in the tumblers F when said tumblers are pressed inward and against the said outer key-guide c', thereby holding said tumblers out of engage-

ment with the notches in said shackle-arms, 15 and a key composed of a shank having a number of removable lugs and a dovetailed slot and slide adapted to lock said lugs in position in said shank substantially as described and for the purpose set forth. 20

In witness whereof I have signed this specification, in the presence of two subscribing witnesses, this 30th day of July, 1898.

WILLIS M. THOMPSON. [L. S.]
